CLAIM

The ornamental design for a cleaning paper dispenser, as shown and described.

DESCRIPTION

FIG. 1 is a top, front, and right side perspective view of a cleaning paper dispenser showing my new design;

FIG. 2 is a top plan view thereof;

FIG. 3 is a front elevational view thereof;

FIG. 4 is a rear elevational view thereof;

FIG. 5 is a right side elevational view thereof; and,

FIG. 6 is a vertical cross-sectional view thereof, taken along line 6—6 of FIG. 3.

The broken-line disclosure of cleaning paper is shown for illustrative purposes only and forms no part of the claimed design.
